UNITED STATES PATENT OFFICE

LÉON V. SOLON, OF NEW YORK, N. Y., ASSIGNOR TO UNITED STATES QUARRY TILE COMPANY, OF PARKERSBURG, WEST VIRGINIA, A CORPORATION OF DELAWARE

DESIGN FOR A TILE

Application filed June 20, 1932. Serial No. 44,134. Term of patent 7 years.

To all whom it may concern:

Be it known that I, LÉON V. SOLON, a citizen of the United States, residing at New York, in the county of New York and State of New York, have invented a new, original, and ornamental Design for a Tile, of which the following is a specification, reference being had to the accompanying drawing, forming part thereof, in which:

Fig. 1 is a plan view of the tile showing the new design.

Fig. 2 is a sectional view taken on line 2—2 of Fig. 1, and

Fig. 3 is a sectional view taken on line 3—3 of Fig. 1.

I claim:

The ornamental design for a tile as shown.

LÉON V. SOLON.
